UNITED STATES PATENT OFFICE.

EDWARD S. STIMPSON, OF HOPEDALE, MASSACHUSETTS, ASSIGNEE TO DRAPER CORPORATION, OF HOPEDALE, MASSACHUSETTS, A CORPORATION OF MAINE.

FILLING CLAMPING AND PARTING MECHANISM FOR LOOMS.

1,427,423.

Specification of Letters Patent. Patented Aug. 29, 1922.

Application filed October 20, 1921. Serial No. 509,078.

To all whom it may concern:

Be it known that I, EDWARD S. STIMPSON, a citizen of the United States, and resident of Hopedale, county of Worcester, State of 5 Massachusetts, have invented an Improvement in Filling Clamping and Parting Mechanism for Looms, of which the following description, in connection with the accompanying drawing, is a specification, like 10 characters on the drawing representing like parts.

This invention relates to automatic filling replenishing looms wherein the running filling is replenished prior to complete exhaustion and wherein the old or spent filling is 15 parted between the cloth and the shuttle by parting means mounted upon a carrier, such as the usual swinging shuttle feeler, so as to be moved bodily rearwardly and forwardly, or toward and from the lay.

The object of the invention is to provide an improved, simple and effective means for operating the filling clamping and parting device when, and only when, a fresh filling 25 carrier is transferred from the magazine or supply to the lay.

The object of the invention is further to provide a construction which may be readily adapted to existing looms.

30 The object of the invention is further to provide a construction which will yield upon the occurrence of an abnormal resistance to the operation of the filling clamping and parting device.

35 The object of the invention is further to provide a construction which eliminates the necessity of special accuracy in the assembling, positioning and adjusting of the filling clamping and parting mechanism.

40 The object of the invention is further to provide means for insuring the proper opening and closing of the filling clamping and parting means and to prevent the possibility of undesirable opening of the filling clamping 45 and parting means which might release the filling end so that it would be drawn into the fell of the cloth.

50 The object of the invention is further to provide a filling clamping and parting device having a single instrumentality operable by a suitable actuator to close said filling clamping and parting means and which is also operable by other mechanism to open

said filling clamping and parting means during the positioning movement thereof.

These and other objects and features of the invention will more fully appear from the following description and the accompanying drawings and will be particularly pointed out in the claims.

In the drawings:

Fig. 1 is a transverse section of a portion of an automatic filling replenishing loom, with a preferred form of the present invention embodied therein, showing the filling 65 clamping and parting means in the forward or retracted clamping position;

Fig. 2 is a detail elevation showing the filling clamping and parting means positioned to engage the running filling from a 70 shuttle just prior to transfer; and,

Fig. 3 is a detail plan view of the filling clamping and parting device and mechanisms for actuating the same in the position illustrated in Fig. 2.

The construction above illustrated is that of the well known "Northrop" type of automatic filling replenishing loom and as this construction is familiar to those skilled in the art no detailed illustration or description, beyond the features particularly concerned with this invention, is necessary.

The broad feature of insuring the operation of the filling clamping and parting means when, and only when, a fresh filling 85 carrier is transferred from the magazine to the lay is disclosed in the patent to Davis No. 1,084,878, granted January 20, 1914, and this patent also serves to illustrate the general type of mechanism in connection 90 with which a preferred form of the present invention is herein illustrated.

The present invention is also subordinate to similar inventions made the subject matter of applications, filed by me May 14, 1921, 95 Serial Numbers 469,508 and 469,509 to which reference may be made for an elaboration of the principles involved. In the construction illustrated in those applications the actuator comprises means adapted to 100 engage and open the filling clamping and parting means during the positioning movement of said filling clamping and parting means. One of the principal differences presented by the present invention comprises 105 a separate means for opening the filling

clamping and parting means during the positioning movement of the latter, the means for thus opening the filling clamping and parting device being so located that 5 any abnormal movement of the filling clamping and parting device, after the filling end has been parted and clamped, will not release the filling end.

More specifically the invention comprises 10 a switch cam adapted to open the filling clamping and parting device during its positioning movement by engaging the same stud as that which is engaged by the actuator to close said clamping and parting device.

The present application is also a continuation in part of the prior application No. 469,508 in respect to the actuator-supporting bracket which is mounted upon the 20 magazine adjacent to the yieldable filling carrier support, the present invention further introducing a switch cam mounted upon said bracket for causing the opening of said filling clamping and parting means.

25 The lay 1, the transerrer 2 which, upon call for filling replenishment, acts to transfer the filling carrier or in this case the bobbin 3 from the magazine or hopper 4 to the lay, or in this case the shuttle 5 at the 30 replenishing side of the loom; the controlling rock shaft 6 which is rocked upon the indication of substantial exhaustion in the running shuttle and acts to initiate filling replenishment; the breast beam 7; the 35 shuttle feeler arm 8 which rocks and slides on the stud 9, being swung over the lay in front of the boxed shuttle upon the operation of the controlling rock shaft 6 and returned under the action of the spring 10 are parts the construction and operation of 40 which will readily be understood by one familiar with the art such as is disclosed in the patent to Davis above mentioned and the patents therein referred to.

45 The replenishing magazine 4 is provided with the usual guide stop 11 against which the filling carrier or bobbin 3 is brought into position for transfer. The filling carrier to be transferred is yieldingly supported and 50 guided on the side opposite to the stop 11 by the usual movable filling carrier support 12 in the form of a flat finger located adjacent the inner face of the magazine. This supporting finger 12 is connected to a stud 55 13 extending through the side of the magazine and carrying on the opposite side an arm 14. A spring 15 is held between a lug 16 on the magazine and the head 17 of a slide rod 18 connected with the arm 14, the 60 rod being guided in the lug. The stop 11 thus forms one side of a throat through which the filling carrier passes from the magazine to the lay, the filling carrier support or finger 12 forming the other side. 65 When the transerrer 2 is operated to trans-

fer a fresh filling carrier from the magazine to the lay, this filling carrier support yields and supports and guides the filling carrier as it passes to the lay.

The filling clamping and parting device 70 may be of any suitable form and construction and is shown as generally similar to that illustrated in the patents above referred to. This device is also shown as supported and carried by the usual shuttle 75 feeler 8. The movable blade 19 co-operates with fixed blades, one of which is shown at 20, and the movable blade 19 secures its opening and closing movement about the pivot 21.

80 When a replenishment of filling is called for the shaft 6 is rocked in the usual manner raising the arm 22 extending rearwardly therefrom and therethrough rocking the shuttle feeler 8 toward the lay. If the shuttle 85 is properly boxed this feeler will pass in front of the shuttle in the usual manner and the dog 23 will be brought into the path of a bunter on the lay and thereupon the transerrer 2 will be operated to transfer 90 the filling carrier 3 from the magazine to the lay therebeneath.

When the shuttle feeler thus swings rearwardly over the lay the filling extending from the filling carrier to be abandoned 95 enters between the members of the filling clamping and parting device which are then in open position. In the case of the type of mechanism to which this invention relates the filling clamping and parting device is 100 closed to clamp and part the filling when, and only when, a filling carrier is actually transferred by the transerrer from the magazine to the lay. Consequently, if the shuttle be improperly boxed so that it is 105 struck by the shuttle feeler, or if the conditions are such that the shuttle feeler, no matter to what extent it may move, does not effect a filling transfer, or if for any reason the filling transfer does not actually take 110 place then there can be no severance of the filling by the filling clamping and parting device.

This result is secured in the present invention by operating the filling clamping and 115 parting device through the movement of the filling carrier support 12 which only moves when actual transfer takes place.

The present invention provides a yieldable operative connection between this filling carrier support 12 and the filling clamping and parting device when in operative position so that in case of any abnormal resistance to a relative movement between these parts there will be no danger of a 120 smash or of damage to the loom.

In the present construction a supporting bracket 24 is adjustably secured to the magazine or hopper 4 by a bolt 25 which passes through a slot 26 in said bracket so that the 130

bracket may be adjusted to any desired position and locked therein by a nut 27 upon the bolt 25. This supporting bracket carries a horizontal stud 28 which serves as 5 the fulcrum for an actuating lever by means of which the movement of the filling carrier support 12 is transferred to the filling clamping and parting device. The yieldable feature of this form of invention is effected 10 by making the actuator lever flexible. For this purpose it is made of stout spring wire so proportioned that under normal conditions it has sufficient rigidity to effect the clamping operation, but under abnormal 15 resistance to a relative movement between the filling carrier support and the filling clamping and parting device it will flex or yield.

This actuator lever is shown as wound in 20 spiral form at 29 to form a fulcrumed hub fitting over the stud 28. One arm 30 of the lever is bent into U-shape and fits over a stud 31 projecting laterally from the arm 14 connected with the filling carrier support 12. The other arm 32 of the actuator lever is provided with a downwardly bent portion 33, a laterally bent portion 34, and a forwardly bent portion 35 which forms a foot positioned to oscillate vertically in a plane 25 which intersects the path of movement of an actuator engaging instrumentality which, in the present instance, is in the form of a pin or stud 36 extending laterally from the movable member 19 of the filling clamping 30 and parting device.

The present construction differs from the construction illustrated in the prior application No. 469,508 in that the downwardly bent portion 33 of the actuator is entirely 40 out of the path of movement of the stud 36 upon the filling clamping and parting device, and in the present construction said actuator is operable only to close the positioned filling clamping and parting device 45 upon transfer. When transfer takes place the filling carrier support 12 is rocked by the actual transfer of the filling carrier from the magazine to the lay in the filling replenishing operation. Then the actuator 50 lever will be rocked about the stud 28, thus raising the foot 35 of the actuator and engaging the stud 36 upon the movable member 19 of the filling clamping and parting device and effecting the clamping and part- 55 ing of the filling. If for any reason whatever there is an abnormal resistance to relative movement between the filling carrier support and the movable member of the filling clamping and parting device then 60 the actuator lever will flex or yield and thus no injury or damage will occur to any of the parts.

After the clamping and parting operation has taken place the shuttle feeler swings 65 forwardly carrying the end of the filling

extending to the fell and moves into the position illustrated in Fig. 1; consequently, the filling clamping and parting device must be brought to open position before it can again function. In the present invention 70 this result is secured by the provision of a switch cam mounted upon the bracket 24 and which lies in the path of the stud 36 of the filling clamping and parting device during its positioning movement, that is to 75 say, during the movement of the filling clamping and parting device into the position in which it is adapted to engage the filling running from the fell of the cloth to the shuttle. 80

In the preferred construction illustrated herein a gravity switch cam 37 is freely pivoted upon a stud 38 which is secured in a slot 39 in an upwardly turned flange 40 of a plate 41 which is adjustably secured to 85 a web or flange 42 extending laterally from the bracket 24. The switch cam 37 is provided with a laterally extending lug 43 which engages the end of the flange 40 and limits the rearward movement of the switch cam. 90 The switch cam is also provided with a lower inclined cam face 44 and a rear vertical face 45 which are adapted respectively to be engaged by the stud 36 upon the rearward and forward movements of the filling clamping 95 and parting device, the cam face 44 acting to open the members of the filling clamping and parting device during the rearward or positioning movement of the filling clamping and parting device, while the engagement of 100 the stud 36 with the vertical face 45 serves to swing the switch cam about its pivot during the forward movement of the filling clamping and parting device without opening the latter, since the switch cam is merely 105 moved about its pivot during the return or forward movement of the filling clamping and parting device.

In the preferred construction illustrated herein the adjustment of the plate 41 is provided by a bolt and slot connection comprising a slot 46 in the flange or web 42 which receives a bolt 47 which passes through the plate 41 and web 42. 110

Desirably the plate 41 is provided with a slot 48 which receives the vertical portion 33 of the actuator lever and serves to steady it in its movement and to prevent undue flexing thereof.

It will be observed that in the operation 120 of the device the rearward positioning movement of the filling clamping and parting mechanism, which results from the movement of the controller arm upon call for transfer, first causes the stud 36 to engage 125 the cam face 44 of the switch cam 37 which lies in its path, causing the cam face of said switch cam to depress the stud 36, thereby opening the filling clamping and parting means. Further rearward movement of the 130

filling clamping and parting means positions the same so that the running filling passes between the movable and stationary jaws of the filling clamping and parting device.

The transfer of the filling carrier from the magazine to the hopper operates the filling carrier support and through it the actuator lever, as above described, causing the 10 foot 35 of said actuator lever to raise the stud 36 and thereby cause the movable member 19 of the filling clamping and parting device to clamp and part the filling. After transfer has been effected the filling clamping and parting device is moved forward to the position illustrated in Fig. 1. During such movement the stud 36 strikes against the vertical face 45 of the switch cam and swings the cam forwardly. Since there is 20 no resistance to the forward movement of the switch cam 37 this engagement of the pin 36 does not serve to actuate the movable member 19 of the filling clamping and parting device, and the filling end, therefore, is held until released by the next 25 positioning movement of the filling clamping and parting device.

It will be understood that the particular embodiment of the invention disclosed herein is illustrative and not restrictive and that various changes in form, construction and arrangement of parts may be made within the spirit and scope of the following claims.

Having thus described my invention, what 35 I claim as new, and desire to secure by Letters Patent, is:

1. An automatic filling replenishing loom comprising a lay, a replenishing magazine for the fresh filling carriers, means for 40 transferring a fresh filling carrier from the magazine to the lay, a filling clamping and parting device movable into a position to receive the running filling when the lay is in position for transfer, the said filling clamping and parting device having an instrumentality to be engaged by an actuator to effect the closing of the clamping and parting device, an actuator, located out of the path of movement of said actuator engaging instrumentality during the positioning movement of said clamping and parting device, actuated by or through the transfer of 45 the fresh filling carrier from the magazine

to the lay and having means to engage and actuate said instrumentality to effect the 55 closing of said clamping and parting means, and a gravity switch-cam mounted on said magazine, located in the path of said actuator engaging instrumentality and acting upon said actuator engaging instrumentality to open said clamping and parting means during the positioning movement thereof.

2. An automatic filling replenishing loom comprising a lay, a replenishing magazine 60 for the fresh filling carriers, means for transferring a fresh filling carrier from the magazine to the lay, a filling clamping and parting device movable into a position to receive the running filling when the lay is in position for transfer having a laterally extending stud adapted to be engaged by an actuator to effect the closing of said clamping and parting device, a filling carrier support 65 pivotally mounted on the magazine and movable by the filling carrier upon its discharge from the magazine to the lay, a supporting bracket rigidly mounted upon the magazine, a flexible actuator lever fulcrumed on said bracket engaging with one 70 arm the pivoted filling carrier support and having its other arm provided with a downwardly extending portion located out of the path of said stud followed by a laterally offset foot portion extending into the plane of 75 the path of movement of said stud and operable by the movement of the filling carrier support, during transfer, to engage and actuate said stud to effect the closing of said 80 clamping and parting device.

3. An automatic filling replenishing loom comprising the construction defined in claim 2, together with means carried by said bracket for opening said clamping and parting means during the positioning movement 95 thereof.

4. An automatic filling replenishing loom comprising the construction defined in claim 2, together with a switch cam carried by said bracket and located in the path of said stud acting to open said clamping and parting means during the positioning movement thereof.

In testimony whereof, I have signed my name to this specification.

EDWARD S. STIMPSON.
